UNITED STATES PATENT OFFICE.

CHARLES A. TATUM, OF NEW YORK, N. Y., ASSIGNOR TO WHITALL, TATUM & CO., OF SAME PLACE.

DESIGN FOR A BOTTLE.

SPECIFICATION forming part of Design No. 21,285, dated January 5, 1892.

Application filed October 31, 1891. Serial No. 410,528. Term of patent 14 years.

To all whom it may concern:

Be it known that I, CHARLES A. TATUM, a citizen of the United States, and a resident of the city, county, and State of New York, have invented and produced a new and original Design for Glass Bottles, of which the following is a full, clear, and exact description, reference being had to the accompanying drawings, forming a part of this specification.

- 10 In accordance with this design glass bottles oblong in cross-section are provided with a distinguishing characteristic, consisting, mainly, of the peculiar shape or configuration of the sides and corners. The design consists, therefore, in this peculiar shape or configuration which I have given to an oblong glass bottle.

In the drawings, Figure 1 is a vertical section on the line 1 1 of Fig. 2 of a glass bottle

oblong in cross-section embodying my design; and Fig. 2 is a cross-section taken on the line 2 2, Fig. 1, of the same.

The oblong bottle A has rounded corners or curves B, which unite the flat faces b and the flat sides a. It will be seen that the faces b are wider than the sides a. These faces b and sides a are united to the bottom D and to the neck of the bottle by curves or rounded corners f f, as shown.

What I claim is—

The design for a glass bottle having flat wide faces b and flat narrow sides a and rounded corners B and f, substantially as herein shown and described.

CHARLES A. TATUM.
